UNITED STATES PATENT OFFICE.

ADOLPH F. LONK, OF CHICAGO, ILLINOIS.

KEY-FASTENER.

1,380,990.

Specification of Letters Patent. Patented June 7, 1921.

Application filed May 27, 1920. Serial No. 334,662.

To all whom it may concern:

Be it known that I, ADOLPH F. LONK, a citizen of the United States, residing at Chicago, in the county of Cook and State 5 of Illinois, have invented certain new and useful Improvements in Key-Fasteners, of which the following is a specification.

The object of this invention is to provide a simple and inexpensive device which may 10 be readily applied to any door and so disposed as to cover the keyhole of the door lock and prevent the key being pushed from the lock by a person outside the door.

The invention is illustrated in the accompanying drawing, in which—

Figure 1 is a perspective view of the device in operative position;

Fig. 2 is an elevation of the same with a door key indicated in section and the inoperative position of the fastener indicated by dotted lines;

Fig. 3 is a detail perspective view of the device.

In carrying out my invention, I provide a blank of sheet metal which may be struck up in a stamping machine and comprises a main bar or shank 1 having tongues 2 projecting from its opposite edges intermediate its ends. These tongues are bent over so as 25 to lie parallel with the opposite faces of the shank and through the shank and each tongue alined openings 3 are provided to permit the insertion of a fastening screw 4 therethrough into the door so as to pivotally 30 attach the device to the door. One end of the shank is provided with a notch 5 in that edge which, in the operative position of the device, is the upper edge and from the lower edge of the shank in vertical alinement with 35 the said notch a covering lip 6 depends, the said lip being of sufficient area to entirely cover the keyhole below the key-receiving portion thereof. The shank is extended, as shown at 7, beyond the notch 5 and the lip 40 so as to strengthen the device adjacent the said notch by providing a sufficient body of material thereat to prevent the device being easily bent so that it will not properly engage the door key. At the opposite end of 45 the shank oppositely disposed longitudinally extending flanges 8 are provided upon the upper and lower edges of the same and these flanges facilitate the manipulation of the device as will be readily understood. The 50 opposite disposition of the tongues 2 as well as the opposite arrangement of the flanges 8 permit the device to be applied to either a

right or left-hand door and the said tongues 2, furthermore serve to offset the device from the door so that the shank will not 60 have to be bent or distorted in order to clear the escutcheon of the lock.

As will be readily understood from what has been said, the fastener is pivotally mounted upon a door, indicated at 9, by inserting a pivot screw 4 through the tongues 2 and the shank 1 into the door, the said pivot being so located that when the shank 65 is in a horizontal position it will extend over the escutcheon 10 of the door lock. 70 After the key 11 has been turned so as to throw the bolt of the lock, the shank 1 is turned upwardly to the horizontal position, shown in Fig. 1 and in full lines in Fig. 2, whereupon the notch 5 will engage the stem 75 of the key and will support the same and the covering lip 6 will entirely cover and close the keyhole slot in the escutcheon 10 and in the door. Any attempt by an outsider to then push the key from the lock in 80 order to permit the bolt to be withdrawn by a false or master key will be frustrated inasmuch as the keyhole slot is covered by the lip 6 against which the blade or wing of the key will impinge when it is attempted to 85 thrust the key from the door. Moreover, the lip 6 will prevent a person outside the door from spying through the keyhole upon the occupants of the door.

My device is obviously very simple in its 90 construction and may be produced at a trifling expense. It is easily manipulated by any person and is very efficient for the purposes for which it is designed.

Having thus described the invention, what 95 is claimed as new is:

1. A device for the purpose set forth comprising a shank provided intermediate its ends with offset pivot-receiving tongues and provided at one end in one edge with a key-engaging notch and upon its opposite edge with a keyhole-covering lip in alinement with said notch. 100

2. A device for the purpose set forth comprising a shank provided with oppositely 105 extending longitudinal flanges at one end and at its opposite end in one edge with a key-engaging notch and on the opposite edge with a keyhole-covering lip, and pivot-receiving tongues extending from the opposite edges of the shank intermediate the ends thereof. 110

In testimony whereof I affix my signature.
ADOLPH F. LONK. [L.s.]
